UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

TEMPORARY BINDER.

1,090,183.

Specification of Letters Patent. Patented Mar. 17, 1914.

Application filed March 3, 1913. Serial No. 751,914.

To all whom it may concern:

Be it known that I, GEORGE P. WIGGINTON, a citizen of the United States, residing at Kalamazoo, Michigan, have invented certain new and useful Improvements in Temporary Binders, of which the following is a specification.

This invention relates to improvements in temporary binders.

10 My present improvements are particularly designed by me for embodiment in a binder of the type shown in Letters Patent #1,010,556, issued to me December 5, 1911, and are an adaptation and in some respects, 15 an improvement upon the structure there illustrated.

The main objects of this invention are: First, to provide in a temporary binder or loose-sheet holder, an improved adjusting 20 mechanism. Second, to provide an improved temporary binder or loose-sheet holder which is capable of very rapid manipulation to permit the removal or insertion of leaves, and one in which the sheets 25 may be very securely clamped, the mechanism simple and compact.

Further objects, and objects relating to structural details, will definitely appear from the detailed description to follow.

30 I accomplish the objects of my invention by the devices and means described in the following specification.

The invention is clearly defined and pointed out in the claims.

35 A structure which is a preferred embodiment of my invention is clearly illustrated in the accompanying drawing forming a part of this specification, in which:

40 Figure I is a detail inside plan view of a structure embodying my invention with the covers extended, the leaves being shown in an upright position. Fig. II is an enlarged detail section on a line corresponding to line 2—2 of Fig. I. Fig. III is an inverted 45 detail view of the binder adjusting mechanism. Fig. IV is an enlarged detail section through the adjusting mechanism, on a line corresponding to the broken line 4—4 of Fig. III. Fig. V is a detail view of the 50 adjusting pinion and its support, a portion of the support being broken away to show the arrangement of the pinion therein. Fig. VI is a view showing connections for the back strip 6 to the adjusting member 7. 55 Fig. VII is a detail inside plan view of a

modified structure, the binder being shown open and the leaves in an upright position. Fig. VIII is a detail section on a line corresponding to line 7—7 of Fig. VII. Fig. IX is an inverted detail of the rack bar and the adjusting slide 27 of the modification of Fig. VII. 60

Referring to the drawing, the covers 1 and 2 in the embodiment of my invention illustrated, are substantially the same in structure as that of my patent hereinbefore referred to. The clamping bars 3 are pivotally connected to the covers as by the hinges 3'. The binding cords or members 4 are secured to the cover 1 and adjustably 70 connected to the cover 2. The cover 2 is provided with a recess 5 for the adjusting mechanism and with a chamber 5' at the rear of the recess for the back strip 6. The adjusting member 7 for the binding members 4 is slidably mounted on a rack 8 arranged longitudinally of the cover recess. The adjusting member 7 is preferably 75 formed of sheet metal with loops 9 struck down therefrom to slidably engage the rack 80 bar 8. See Figs. I, II and III. A pawl 10 is pivoted on the adjusting member 7 at 11 to coact with one edge of the rack bar, the rack bar being, in the structure illustrated, provided with teeth on each edge. 85 The adjusting member is provided with a segmental slot 12 through which the finger piece 13 of the pawl is arranged. The pawl 14 is held yieldingly in its engaging and disengaging positions by means of the U-shaped 90 spring 14, one arm of which is mounted on the pivot 15 and the other engages the pawl. See Fig. III. The spring 14 is thus adapted to hold the pawl in either its engaging or disengaging positions, substantially 95 as in the structure of my said patent.

To tighten the binding strips or apply clamping stress thereto, I provide a pinion 16 which is arranged in a cup-like seat 17 in the support 18. This support is a sheet 100 metal stamping, the seat being struck therefrom and being cylindrical so that the pinion is a turning fit therein. Thus arranged no journals for the pinion are required. The seat is cut away on one side so that the 105 pinion is supported in mesh with the rack bar, as shown in Fig. III. The pinion is provided with a squared hole 19 adapted to receive the tang 20 of the key-like spindle 21. The adjusting member 7 and the pin- 110

ion member support 18 are provided with holes 22 adapted to receive the spindle and constituting bearings therefor. By thus arranging the parts, the adjusting member is actuated to tighten the binding strips or members by means of the key or spindle 21 and is held in its adjusted position by means of the pawl. When it is desired to release the member, the pawl is shifted to 10 inoperative position when the adjusting member moves freely on the bar 8. The back strip 6 is connected to the adjusting member 7, by the spring 33 one end of the spring being secured to the stud 23 extended through the slot 24 in the wall 25. The spring 33 is preferably S-shaped, its other end being connected to the back strip by a suitable clip 34.

In the modification shown in Fig. VI, the 20 adjusting pinion 26 is mounted on the slide 27, the slide being provided with a suitable housing 28 constituting with the slide, bearings for the spindle 29 of the pinion. The spindle 29 is provided with a collar 30 on 25 which the finger piece 31 is pivotally mounted. The slide is provided with diagonally opposed rack engaging lugs 32 which slidably retain the same upon the bar to permit its being engaged and disengaged as desired, the object of this being to permit the use of these adjusting slides on binders such as are shown in my said patent or in the modification shown herein, in which no pinion is provided on the adjusting member. 30 The operation of this modified structure is substantially the same as that of the preferred construction.

My improved binder is very simple and economical in structure and is easily and 40 quickly adjusted. I have illustrated and described my improvements in the form in which I have embodied them.

While I am aware that various modifications in structural details are possible, I 45 have not attempted to illustrate or describe the same herein as I believe they will be readily understood by those skilled in the art to which this invention relates from the disclosures herein made.

50 Having thus described my invention, what I claim is new and desire to secure by Letters Patent is:

1. In a temporary binder, the combination of a binding member, a rack bar toothed 55 on both edges, an adjusting member for said binding member, mounted on said bar, a pawl mounted on said adjusting member to coact with the teeth on one edge of said bar, a spring adapted to hold said pawl 60 yieldingly in its operative and inoperative positions, a pinion mounted on said adjusting member in mesh with the other edge of said bar, and means for turning said pinion.

2. In a temporary binder, the combination 65 of a binding member, a rack bar toothed

on both edges, an adjusting member for said binding member, mounted on said bar, a pawl mounted on said adjusting member to coact with the teeth on one edge of said bar, a pinion mounted on said adjusting 70 member in mesh with the other edge of said bar, and means for turning said pinion.

3. In a temporary binder, the combination 75 of a binding member, a rack bar, an adjusting member for said binding member mounted on said bar, a pawl mounted on said adjusting member to coact with said bar, a spring adapted to hold said pawl yieldingly in its operative and inoperative 80 positions, a pinion mounted on said adjusting member in mesh with said bar, and means for turning said pinion.

4. In a temporary binder, the combination 85 of a binding member, a rack bar, an adjusting member for said binding member mounted on said bar, a pawl mounted on said adjusting member to coact with said bar, a pinion mounted on said adjusting member in mesh with said bar, and means for turning said pinion.

5. In a temporary binder, the combination 90 of a binding member, a rack bar, an adjusting member for said binding member mounted on said bar, means for holding said adjusting member in its adjusted position on said bar, a pinion mounted on said adjusting member in mesh with said bar, and means for turning said pinion.

6. In a temporary binder, the combination 100 of a binding member, a rack bar, an adjusting member for said binding member, mounted on said bar, means for holding said adjusting member in its adjusted position on said bar, a pinion adapted to receive a spindle, and a pinion support mounted on the under side of said adjusting member and provided with a seat in which the pinion is rotatably supported in mesh with said bar, said adjusting member and support being provided with openings adapted 105 to receive the spindle and constituting bearings therefor.

7. In a temporary binder, the combination 110 of a binding member, a rack bar, an adjusting member for said binding member, mounted on said bar, means for holding said adjusting member in its adjusted position on said bar, a pinion, a pinion support mounted on the under side of said adjusting member and provided with a seat in which the pinion is rotatably supported in mesh with the said bar, and means for turning said pinion.

8. In a temporary binder, the combination 115 of a binding member, a rack bar, an adjusting member for said binding member mounted on said bar, a pawl for holding said binding member in its adjusted position on said bar carried by said adjusting member, a pinion support on said adjust- 120

ing member provided with a seat in which the pinion is rotatably supported in mesh with the said rack, and means for turning said pinion.

5. 9. In a temporary binder, the combination of a binding member, a rack bar, an adjusting member for said binding member, mounted on said bar, a pawl for holding said adjusting member in its adjusted position on said bar carried by said adjusting member, and means for actuating said adjusting member comprising a pinion mounted on said adjusting member.

10. In a temporary binder, the combination with the covers, binding strips extending between the covers, a rack bar carried by one of the covers, an adjusting member to which said binding strips are connected, mounted on said rack bar, a pawl on said 20 adjusting member for holding it in its adjusted position on said rack bar, and means for actuating said adjusting member comprising a pinion.

11. In a temporary binder, the combination with the covers of binding strips extending between the covers, a rack bar mounted on one of the covers, an adjusting member to which said binding strips are connected mounted on said rack bar, means 30 for holding said adjusting member in its adjusted position on said rack bar and means for actuating said adjusting member comprising a pinion.

12. In a temporary binder, the combination with the covers of binding strips extending between the covers, a rack bar carried by one of the covers, an adjusting member mounted on said rack bar, said binding strips being connected to said adjusting 40 member, and means for actuating said adjusting member comprising a pinion mounted on said adjusting member.

13. In a temporary binder, the combination with the covers of binding strips ex-

tending between the covers, a rack bar carried by one of the covers, an adjusting member mounted on said rack bar, said binding strips being connected to said adjusting member, and means for actuating said adjusting member comprising a pinion, coacting with said rack.

14. In a temporary binder, the combination with the covers, one of the covers being provided with a chamber open at its inner end, a longitudinally slotted partition plate 55 arranged in one of the cover chambers, a back strip extending between the covers arranged to the rear of said plate, a rack bar arranged in front of said partition plate above said slot therein, a binding strip extending between the covers, an adjusting member for said binding strip arranged on said rack bar, a stud on said adjusting member projecting through said slot, and an S-shaped spring connected at one end to said 60 stud and at the other to said back strip.

15. In a temporary binder, the combination with the covers, one of the covers being provided with a chamber open at its inner end, a longitudinally slotted partition plate 70 arranged in one of the cover chambers, a back strip extending between the covers arranged to the rear of said plate, a rack bar arranged in front of said partition plate, a binding strip extending between the covers, 75 an adjusting member for said binding strip arranged on said rack bar, a stud on said adjusting member projecting through said slot, and a spring connected at one end to said stud and at the other to said back strip. 80

In witness whereof, I have hereunto set my hand and seal in the presence of two witnesses.

GEORGE P. WIGGINTON.
